UNITED STATES PATENT OFFICE.

FRANCIS G. DU PONT, OF WILMINGTON, DELAWARE.

PROCESS OF SEPARATING SOLVENTS FROM SUBSTANCES.

SPECIFICATION forming part of Letters Patent No. 712,406, dated October 28, 1902.

Application filed July 11, 1902. Serial No. 115,117. (No specimens.)

To all whom it may concern:

Be it known that I, FRANCIS G. DU PONT, a citizen of the United States, residing at Wilmington, in the county of Newcastle and State 5 of Delaware, have invented a certain new and useful Process of Separating Solvents from Substances; and I do hereby declare the following to be a full, clear, and exact description of the same, such as will enable others 10 skilled in the art to which it appertains to make and use the same.

My invention relates to a process of freeing nitrocellulose from alcohol-ether, and is particularly intended for use in the manufacture 15 of smokeless powder for extracting the solvent used in colloiding nitrocellulose.

My invention consists in the novel method of extracting the solvent, as hereinafter described, and in the novel steps of the process.

20 The objects of my invention are to facilitate the extraction of solvents from nitrocellulose, and particularly to hasten the hardening and drying of nitrocellulose smokeless powders after colloiding.

25 In the manufacture of nitrocellulose explosives, such as smokeless gunpowder, the nitrocellulose is customarily colloided by the action of a solvent, usually alcohol-ether, and much difficulty is experienced in extract-

30 ing the solvent after the completion of the colloiding action in order that the powder-grains may dry and harden. This difficulty is probably due both to an affinity of the solvent for the nitrocellulose and also to the fact

35 that when the solvent in the outer layers of the powder blocks or grains leaves the latter it deposits on the outer surfaces of such blocks or grains a layer of nitrocellulose, which forms a hard skin or coating, resem-

40 bling somewhat the coating formed by varnish on articles to which it is applied. This skin or coating effectively resists the escape of further portions of the solvent from the interior of the blocks or grains, so that the solvent

45 from the interior can escape only very slowly. In practice it is found that nitrocellulose powder of the sizes used in ordnance requires several months for drying, the exact time depending largely on the size and shape 50 of the grains. By the process herein described I prevent the formation of such a

hard outer coating while the interior is still saturated with the solvent and in addition free the nitrocellulose substantially completely from the solvent by a relatively brief 55 treatment, so that after such treatment the drying may be comparatively rapid.

In the accompanying drawing I illustrate diagrammatically an apparatus which may be used for the carrying out of the process. 60 Said apparatus may consist of a vessel 1, adapted to contain the material to be treated, having at the top a filling-orifice 2, adapted to be closed by a suitable plug, and having at the bottom a pipe 3, through which air may 65 be admitted or liquid contents of the vessel permitted to drain off, said pipe being provided with a regulating-valve 4. From the upper portion of the vessel a pipe 5 may lead to a suction-pump 6, and thence another pipe 70 7 may lead to a condenser 8.

In carrying out my process I place nitrocellulose saturated with the alcohol-ether in the vessel 1 and then introduce alcohol into the said vessel. As is well known, although 75 alcohol-ether readily dissolves nitrocellulose of the higher degrees of nitration neither alcohol nor ether by itself is a solvent of the higher grades of nitrocellulose. Since ether dissolves in alcohol in all proportions, when 80 the nitrocellulose is saturated with alcohol-ether is submerged in an excess of alcohol the ether diffuses itself through the main body of alcohol in the vessel. I then proceed to draw off the ether from the vessel, which may be 85 done in various ways, one of the most convenient being to open the valve 4 slightly and then by means of the suction-pump 6 to draw air upward through the body of alcohol within the vessel 1. Since the boiling-point 90 of ether is much lower than that of alcohol, this air in bubbling up through the mixture of alcohol and ether continuously carries away the ether present in the free alcohol, and as the ether is so removed more escapes 95 from the interior of the powder-grains to dissolve in the surrounding alcohol. By this process, therefore, the ether may be removed continuously until none or practically none remains in the powder-grains. Since the alcohol is not in itself a solvent of the nitrocellulose, it follows that when the latter is re- 100

removed from the alcohol-bath surface drying will not cause the formation of a hard film or skin upon its surface, through which the interior liquid can only escape very slowly, but, 5 on the contrary, the alcohol still within the grains will be left free to evaporate and escape therefrom and will so escape quite rapidly.

While the ether is being taken off, as above 10 described, the apparatus may be maintained at or slightly below the boiling temperature of ether either by maintaining the room in which the apparatus is located at about such temperature or by applying heat to the outer 15 side of the vessel 1 in any other suitable well-known way, and, if necessary, by heating the air entering the pipe 3. The only purpose of heating the air or the vessel 1 is to supply the heat absorbed by the liquid within the vessel 20 1 in its evaporation and to maintain the temperature of such liquid at about the point at which the ether will evaporate most readily. The exhaust from the suction-pump may be led to a suitable condenser and the ether and 25 alcohol carried thereby condensed and saved.

By this process I have found that nitrocellulose may be substantially freed from ether after about one day's treatment in the manner described and that when the powder is 30 removed from the vessel and spread out to dry four or five days' drying suffices to dry and harden it, whereas by the former methods of removing the solvent by evaporation into the air several months are required for 35 drying, and in addition the solvent is lost.

Instead of maintaining the room in which the operation is conducted at or near the boiling temperature of ether at atmospheric pressure or of applying heat to the vessel or to the 40 entering air the vacuum - pump 6 may be caused to reduce the pressure in vessel 1 considerably below atmospheric pressure, thus lowering the boiling temperature of the ether to substantially ordinary atmospheric temperature or even lower. In the latter case it 45 is not necessary to admit air.

In the ordinary method of drying for removing the solvent from nitrocellulose powders the powder-grains dry most rapidly at 50 the ends, and this causes uneven shrinking of the grains and considerable deformation thereof. This is not the case with powder

from which the solvent has been removed by the method above described.

It is obvious that the air admitted through 55 the tube 3 and which in bubbling up through the alcohol carries off with it ether dissolved therein is a mere vehicle for carrying off the ether and that other gases might be used instead of air, if desired. This air will necessarily carry off some alcohol, since alcohol evaporates slowly at ordinary atmospheric temperatures; but the proportion of alcohol carried off with respect to the ether will be very small, and this step of the process 60 amounts, in effect, to a separation of the ether from alcohol. The vapors carried off are caught in the condenser and there condensed, so that the ether may be used over again.

It is obvious that my process may be varied 70 to a considerable extent in carrying it out, and I do not limit myself to the particular details of the process herein described.

What I claim is—

1. The herein-described process of extracting from nitrocellulose a solvent comprising a plurality of ingredients, which separately are not solvents of nitrocellulose, which consists in subjecting such nitrocellulose and solvent to the action of an excess of one of the 80 ingredients of such solvent.

2. The herein-described process of extracting from nitrocellulose a solvent comprising a plurality of ingredients, which separately are not solvents of nitrocellulose, which consists in flooding such nitrocellulose and solvent with an excess of one of the ingredients of the solvent.

3. The herein-described process of extracting alcohol-ether from nitrocellulose, which 90 consists in flooding the nitrocellulose carrying the alcohol-ether with an excess of alcohol.

4. The herein-described process of extracting alcohol-ether from nitrocellulose, which consists in immersing nitrocellulose carrying 95 the alcohol-ether in alcohol and causing a gas to pass through the alcohol, thereby carrying off the ether in solution therein.

In testimony whereof I affix my signature in the presence of two witnesses.

FRANCIS G. DU PONT.
